Highland Park, Mich., a corporation of Delaware

Application October 20, 1937, Serial No. 169,936

2 Claims. (Cl. 62—129)

My present invention relates to an improvement in air conditioning units having incorporated therein improved means for controlling the humidity and temperature of the enclosure with which the unit is associated. The purpose of my invention is to render the control of conditions more accurate and reliable and to lessen the cost of air conditioning. In accordance with my invention the control of temperature and humidity may often be accomplished by increasing or decreasing the amount of fresh air sent through the unit thereby lessening the amount of refrigeration or heating by mechanical means.

Further objects and advantages of my invention will be apparent from the following description taken in connection with the accompanying drawings wherein Fig. 1 is a vertical section taken through the air conditioning unit along the line 1—1 of Fig. 2, looking in the direction of the arrows; Fig. 2 is a horizontal cross-section through the unit taken along line 2—2 of Fig. 1, looking in the direction of the arrows; Fig. 3 is a vertical section taken through the unit along line 3—3 of Fig. 1, looking in the direction of the arrows; Fig. 4 is a schematic diagram of the unit showing the same with the dampers set in one position so that all the air passing through the unit is recirculated air; Fig. 5 shows a second position of the dampers in which all of the air passing through the unit is fresh air which remains at its natural temperature and humidity; Fig. 6 shows a third disposition of the dampers in which all the air is recirculated air passing through a cooling and humidifying spray; Fig. 7 shows a fourth position of the dampers in which fresh air is introduced without change of state and recirculated air passes through the spray; Fig. 8 shows a fifth position of the dampers in which all of the air is recirculated air passing through a heating coil; Fig. 9 shows a sixth position of the dampers in which fresh air is passed through the cooling coil and a certain amount of recirculated air is admitted; Fig. 10 shows a seventh position of the dampers in which recirculated air passes through the spray; and Fig. 11 is a wiring diagram of the unit showing the means for controlling the dampers to operate in the manner described.

In Fig. 1 there is disclosed a unit 10 comprising a fresh air passage 11 having access to air outside the enclosure and a recirculated air passage 12 through which air from the enclosure is drawn, the unit having a blower 13 therein by means of which the air is drawn into the unit and ejected through a discharge passage 14. The unit

is supported on legs 15, 16 to which are attached motor supports 17 and 18 supporting damper motors 19, 20 and 21. Beneath the unit there is situated a compressor 25 which compresses a refrigerating medium into discharge pipe 26. The discharge pipe is provided with a solenoid valve 27 which prevents the refrigerant from passing into a water-cooled condenser 28, the refrigerant then passing into a branch discharge pipe 29 also provided with a solenoid valve 10 30 which leads to heating coils 31 and 32 connected by a header 33 and a return header (not shown). The refrigerant gas which passes through the heating coils 31 and 32 passes through pipe 34 into the water-cooled condenser 15 28. The condenser is supplied with cooling water through pipes 35 and 36, the flow of cooling water being preferably controlled by a thermally responsive valve so as to economize on water consumption (such valves being well-known in the art and hence not shown). The cooled liquefied refrigerant then flows through pipe 37 to an expansion valve 38 admitting liquid into the cooling coil 39 where by expansion a low temperature is realized. The gas is then drawn through suction pipe 40 into the compressor and the cycle of refrigeration repeated.

It is apparent from Figs. 1 and 2 that the heating and cooling coils are situated within the unit in such position that normally only recirculated air could be drawn through them. However, a study of Figs. 5 to 10 shows the manner in which fresh air or recirculated air can be drawn through the coils in various fashions to accomplish various purposes. The following description will serve to clarify the operation of the unit in order to economize on power consumption by accomplishing the control of heating, cooling, humidifying or dehumidifying by means of controlling the amount and direction of air flow.

This control is accomplished by means of dampers shown in Figs. 1, 2 and 3. In the fresh air passage 11 there is situated a damper 50 which prevents the entrance of fresh air into the unit when in closed position. Damper 50 when in open position permits the entrance of fresh air and a second damper 51 causes fresh air to pass directly into the room when in open position and to pass vertically downward through the cooling coil 39 through opening 52 when in closed position. A set of face dampers 53 are situated at the entrance of the recirculated air passage 12 and prevent the entrance of recirculated air to the cooling coil 39 when in closed position. A set of

three rear dampers 54 are located behind the cooling coil 39 and permit air to pass through the cooling coil from front to rear when dampers 53 and 54 are both open. Dampers 54 form with 5 the face dampers 53 the walls of a passage causing fresh air to pass downward through the cooling coil 39 when both sets of dampers are closed. At each side of the recirculated air passage 12 there are recirculated air by-pass passages 55 10 and 56 leading recirculated air to heating coils 31 and 32, respectively. The entrance to passage 55 is controlled by a set of three dampers 57 and a similar set of three dampers 58 acting in unison therewith controls the entrance to passage 56. 15 In front of heating coil 31 there are two dampers 59 and 60 acting together and a third damper 61 acting in a contrary fashion. Similar dampers are situated in front of coil 32, the corresponding dampers acting in the same manner as dampers 59, 60 and 61. Damper motor 19 is connected by link 65 to the dampers 57 which are connected together by link 66 and to the dampers 54 by means of links 67 and 68. Link 67 is also connected to dampers 53 which are connected 20 together by a link 69, so that when dampers 57 are open dampers 53 and 54 will be in closed position and vice versa. Situated beneath the cooling coil 39 is a passage 70 through which air directed downwardly through the cooling coil 39 25 can be by-passed around dampers 54 when damper 71 is in open position. Damper motor 20 is connected to damper 71 by a link 72, which is in turn connected to damper 61 by a link 73, which is in turn connected to damper 51 by a link 74. When dampers 71 and 61 are in closed 30 position damper 51 will be in open position and vice versa. Damper motor 21 is connected to dampers 59 and 60 by a link 75 which is in turn connected to damper 50 by a link 76. When 35 damper 50 is closed dampers 59 and 60 will be open and vice versa.

Referring to Fig. 4 the apparatus is shown diagrammatically in one position, for purposes of illustration passage 56 and heating coil 32 having been eliminated since the operation thereof is identical to the operation of passage 55 and heating coil 31. In this view damper 50 is closed, shutting off the supply of fresh air. Dampers 53 are closed, shutting off the flow of recirculated 40 air through cooling coil 39. Dampers 57 are open thereby limiting the operation of the unit to treatment of return air. Since damper 50 is in closed position dampers 59 and 60 are in open position. Also, dampers 71 and 61 are in closed 45 position and damper 51 in open position. The flow of air through the heating coil is therefore limited to the amount which can pass through the open dampers 59 and 60.

In Fig. 5 the dampers remain the same except 50 that dampers 50, 59 and 60 are reversed in position. This causes the complete blocking off of recirculated air and an unrestricted flow of fresh air through passage 11. In Fig. 6 the fresh air passage 11 is blocked off and the passage 55 is 55 likewise blocked off while the passage 12 directly through the cooling coil is open for the admission of recirculated air to the cooling coil.

Fig. 7 discloses the dampers in such position 60 that the fresh air passage is entirely open and the recirculated air passage 12 is also entirely open so that the air is divided between the two passages. The air flowing through passage 12 flows through coil 39 in the narrow direction, which is to say that in one embodiment of my 65 invention the air passes through three rows of

tubes. Due to the resistance of the coil the amount of air flowing through one passage would be substantially the same as that flowing through the other passage. Fig. 8 discloses the dampers in such position that all the air admitted to the unit is recirculated air which passes through the heating coils 31 and 32. Fig. 9 shows the dampers in such position that air is entering through the fresh air passage 11 and traversing the wide dimension of the coil which in the same embodiment of my invention as mentioned above means that the air passes through nine rows of coils. Recirculated air also passes through the passage 55 in an amount as permitted by the open damper 61. Fig. 10 discloses the dampers in such position that all of the air is recirculated air passing through the passage 12 in the narrow direction of the coil. The purpose of each damper position will be more fully explained while explaining the control means for operating the dampers and other elements of the unit.

In addition to the cooling and heating coils previously described there is also placed in the unit a pipe 80 provided with spray nozzles 81 by means of which a fine mist may be created in 25 the passage 12 so that air passing through this passage has its vapor content increased and is lowered in temperature by the evaporative cooling of the water sprayed into the passage.

Referring to Fig. 11 there is set forth a wiring 30 diagram for the above form of my invention. In this diagram the fresh air damper motor 21, the face and by-pass damper motor 19 and the seasonal damper motor 20 are indicated schematically and are shown as being provided with a 35 plurality of cams for the purpose of making contacts at various positions of the dampers. A motor 85 is provided for a motorized steam valve which may be operated to admit steam to the ordinary radiators or other heating means of a 40 heating system (not shown). The valve 30 between the compressor and the coils 31 and 32 and the valve 27 between the compressor and the water-cooled condenser are shown in their relative positions, there being no control for the 45 spray through pipe 80 since the same is intended to operate at all times unless manually shut off during seasons of high humidity.

In order to explain the operation of the system let us assume that it is winter and the room 50 is at 74° d. b., 50% r. h. and the room thermostat 86 and room humidostat 87 indicate that this condition is satisfactory. The outside air is lower in both wet bulb temperature and absolute 55 humidity than the room condition; for example, 42° d. b., 30% r. h. If the switch 88 is now closed the motor 89 of blower 13 will operate to draw air through the unit since the fan switch causes current to pass from the 110 volt supply 90 through the switch 88 and motor 89 back to supply. 60 Since we have assumed that room conditions are satisfactory the blower will merely circulate air through the unit as set forth in Fig. 4. The compressor will not be running and the reheat coil 31 will therefore have no effect on the air passing 65 through the passage 55, the amount of air recirculated being, by way of example, 1000 cubic feet per minute.

If the room temperature falls the thermostat 70 86 will make at the low contact 91 with the result that current passes from the 24 volt battery 22 through wire 93, wire 94, wire 95, thermostatic element 86, low contact 91, wire 97, wire 98, cam contactor 99 on the motor 89, through the steam valve motor 85, and wire 100 to wire 101 leading 75

back to 92. Thus the motor will be started to open the steam valve. In the zero or closed position of the motor, cam 99 is the only cam to make contact. This cam carries current until the motor has rotated 4°, but at 2° of rotation cam 105 will also close. Thus the circuit before noted and the circuit direct from wire 95 through wire 106, wire 107, cam 105 and the motor 85 carry current in parallel through the motor from 2° to 4° of rotation. At 4° cam 99 breaks contact and the motor runs on the circuit through cam 105 to the 180° position of the motor. Wire 97 will still remain energized through the thermostat contact 91 and current will pass through wire 108, relay coil 109, wire 110, cam contact 111 and wire 112 back to the battery, as soon as cam 111 makes contact at 178° of rotation. By thus energizing coil 109 the switch 113 is held open so that current cannot energize the motor through cam 114. Thus the motor remains in 180° position until the thermostat low contact 91 is broken. Since we are assuming a winter condition with steam on and the compressor not running, the air will continue to be recirculated through the unit, all of the air being recirculated air passing through passage 55 as seen in Fig. 4.

When the temperature in the room rises enough to break contact at 91 relay 109 is no longer energized so that current can flow through cam 114 causing the motor to continue moving in the same direction toward the 360° or zero position. At 182° cam 105 is again closed carrying current to the motor in parallel with cam 114 until at 184° the current can no longer pass through cam 114 and the motor is entirely fed through cam 105 from there on until the 358° position is reached. At 358° cam 115 breaks contact, thus opening a circuit through wire 112, cam 115, wire 116, switch 117, wire 118, relay 119 and wire 120 back to battery 92 which deenergizes the relay 119, opening switch 121 and causing the fan motor to stop so that the fan is no longer circulating air through the room. This completes the control of the apparatus during the operation of heating by recirculating the air over radiators located in the room.

Now if the temperature rises element 96 of thermostat 86 will make the high contact 125 and current will now pass from 96 through 125, 50 through a switch 126 normally in contact with a wire 127, through the wire 128, cam 129, motor 21, and wire 130 to the battery 92. Thus the motor 21 starts and as with respect to the motor 85 is driven to 180° by current passing through wire 94, wire 131, and cam 132 to the motor 21. The fresh air damper 50 is now wide open as shown in Fig. 5 and the reversely linked dampers 59 and 60 are closed so that all of the air, for example, 1000 cfm. is fresh air passing through passage 11. As long as the thermostatic contact 125 is made, relay 133 will keep switch 134 in open position preventing current from passing through wire 135 and cam 136. However, when the outside air has reduced the room temperature enough to break contact 125 the relay 133 will be de-energized, thus starting the motor to travel from 180°, the traveling being continued to 360° by current passing through cam 132, thus closing off the fresh air.

70 I have thus described a method of controlling the temperature in the room during winter, having shown what happens to correct both falling and rising temperatures. Correction must also be made in cases of rising and falling humidities, for which the room humidostat 87 has been

provided. It may be seen that the high contact 140 of humidostat 87 feeds current to line 127 just as the high contact 125 of thermostat 86 fed current to line 127. This means that as long as the temperature, or the humidity, or both the temperature and humidity, is too high line 127 will be carrying current so that the fresh air damper must be opening or standing open. When both high contacts are broken relay 133 will be deenergized causing the fresh air damper to be closing or standing closed. If the humidity falls too low then the low contact 141 of humidostat 87 will be closed and current will flow through line 142 and line 143 to cam 144 of motor 19, through the motor, and line 145 to ground. 10 Again the cam 146, corresponding to cams 105 and 132, will drive the motor to 180°. At this point the dampers are in the positions shown in Fig. 6, the face dampers 53 being open, the rear dampers 54 being open and all other passages 20 being closed. Therefore all of the air, for example, 1000 cfm. will be passing through passage 12 and since the compressor is not operating and the spray through pipe 80 is continuous the air will be humidified. As soon as the humidity has risen to the control point contact 141 will break so that relay 150 will be deenergized causing current to flow through wire 151, switch 152, and cam 153 and the motor 19 will start closing the face and rear dampers. 30

Thus I have control means for both falling or rising temperatures and humidity during the winter months. When neither temperature nor humidity is different from the desired condition all motors will be standing at zero or off position, the fresh air passage and by-pass passage will be closed, and the air will be recirculated without treatment. If the temperature drops the steam valve will be opened and the air will be heated without treatment as to humidity. If 40 the temperature rises too high, the fresh air passage will open, the recirculated air passage will close, the steam valve will be closed, and fresh air will be used to lower the temperature of the room as well as to ventilate as shown in 45 Fig. 5. If the humidity is too low and the temperature agreeable, the fresh air passage will be closed, the passage 55 will be closed and room air will be recirculated through the humidifying 50 spray. If the temperature rises too high and the humidity is still too low the fresh air damper will be opened as shown in Fig. 7 with the result that about 500 cfm. fresh air and about 500 cfm. recirculated air will be drawn through the unit, vapor being added to the recirculated air and 55 the temperature being lowered by the fresh air.

The above describes all of the operations that can be adopted when outside conditions are lower in both wet bulb temperature and absolute humidity than the desired conditions. Of course 60 heating may take place simultaneously with any position of the dampers caused by the humidostat, which means the equipment could be ventilating and heating; humidifying and heating, or recirculating and heating. I have thus shown 65 a method of controlling the temperature and humidity in an enclosure when there is available a free source of cooling and dehumidifying, which is the outside air.

During the summer when the outside air, instead of being at 42° d. b., 30% r. h. as in winter, is at, for example, 83° d. b. and 70% r. h., if the temperature or humidity in the room rises above desired conditions the high contact of either thermostat 86 or humidostat 87 is made with the 75

result that the fresh air damper 50 is opened. This will result in a rise in temperature or humidity in the room, or perhaps both, so that in a short time the temperature will have risen 2° or the humidity 4% over the setting of the controlling instruments 86 and 87. There are also provided a thermostat 160 and a humidostat 161 which are connected in the circuit as follows: From wire 94 a wire 162 leads to the thermostatic element 163 and from wire 94 a wire 164 leads to the humidostatic element 165. These elements are designed to make contact with a wire 166 on the high side of both instruments which wire is connected to wire 167 leading to cam 168 of motor 20, the current passing through the motor and wire 169 to 92. The rise in inside temperature results in current being carried to the motor which causes the motor to start toward 180° and to stop at 180° through the medium of cams corresponding to those previously described for each other motor. When cam 170 is energized current is led from wire 171 through wires 172 and 173 to solenoid 174, thus breaking the contact of switch 126 with wire 127 and causing switch 126 to contact wire 175 which causes the high contact 125 of thermostat 86 to control motor 19 instead of motor 21. It also energizes solenoid 176 through wire 177 and wire 178 so that solenoid 180 will be energized to close switch 181 which causes current to pass from battery 90 through wire 182 to wire 183 which at the point indicated by the arrow leads into control circuits comprising elements such as high and low pressure cut-outs, starting switches, etc., for the compressor motor, the opposite side of the circuit being indicated by wire 184. Such control circuits for compressor motors are well known and would serve no purpose if illustrated in the present drawings. The motors 19 and 20 when rotated to 180° have caused the dampers to assume the positions shown in Fig. 9 thereby causing fresh air to be drawn through the long dimension of the coil 39 and recirculated air to pass through passage 55 in the amounts of about 300 to 600 cfm. respectively. Let us suppose that both the temperature and humidity are now too high. This will keep motor 21 at 180° and the compressor running so that the small amount of air being brought through the long dimension of the coil will be brought to a dew point well below that of the room with the result that room air is being recirculated and mixed with cold, dry, fresh air. If the room temperature now becomes too cold the thermostat 86 will make contact at 91 then the heating motor 85 will be operated to reheat the room. Since switch 181 is closed 110 volt current through line 185, solenoid 186, line 183 and the controls will bring switch 117 to its lower position thereby bringing current through wire 116 to solenoid 187 and through wire 188 to wire 106. 110 volt current will flow through wire 190, switch 191 and wire 192 through solenoid valve 30 instead of through wire 193 and solenoid valve 27; thus solenoid valve 30 is opened and solenoid valve 27 closed causing hot gas from the compressor to go through the reheat coils 31 and 32. If the compressor stops solenoid 186 will allow current to start the steam heat as previously explained. If, however, while the compressor is running the reheat coils raise the temperature sufficiently to break contact 91 then motor 85 will return to closed position and the valves 30 and 27 will be reversed in operation thereby permitting hot gas to go directly to the water cooled condenser.

Assuming that the operation of dehumidifying does not require heating and does not even result in enough cooling to break the contact 125 of thermostat 86 it will be seen that current cannot flow through solenoid 174 because the contacts of solenoid 187 are open. However since the humidity has been corrected, in other words, contact 140 is broken, then motor 21 will go to zero position, the fresh air damper will be closed and solenoid 187 will be deenergized to allow its contacts to close. Then if contact 91 is still made current will be fed to wire 175 which will start motor 19 to open the face dampers. Since the switch 200 is now closed due to the energizing of the solenoid 176 solenoid 180 can establish contact through switch 200 to ground in order to start the compressor. This puts recirculated air through the sprays and the narrow dimension of the coil, thus doing sensible cooling. When the room temperature has dropped sufficiently, contact 125 breaks causing motor 19 to close the face dampers 53 and rear dampers 54, and stopping the compressor.

Thus we can heat, cool and dehumidify in hot and humid weather. The necessity for humidifying will usually be non-existent in this weather. A falling humidity would open the face dampers and subject the recirculated air to spray and would also start the compressor. Starting the compressor would destroy the humidifying effect so that if it were found in practice that humidifying might be necessary, a time relay could be installed which would permit the recirculation of air through the humidifying spray without cooling.

It is obvious that when the equipment is once placed on refrigerating operation through contact in either 86 or 87 the equipment would remain continuously in this position; namely, that shown in Fig. 10 with recirculated air passing through the cooling coil. In order to prevent the room from becoming filled with stale air a synchronous clock driven motor 200 is supplied which once each hour makes contact in the 24 volt line which completes a circuit through line 201 to motor 20 thus returning the mechanism to ventilating operation. If the outside temperature or humidity is still too high to maintain desired room conditions the room temperature or humidity will again mount to make the high contact of thermostat 160 or humidostat 161, thus returning the equipment to the refrigerating operation. Thus the equipment uses refrigeration only when maximum ventilation will not suffice and only as long as necessary since when outside conditions have returned to a cool and dry state low enough to control room temperature and humidity the use of ventilation will suffice and the compressor may be stopped.

It is obvious that I have provided an air conditioning system which automatically controls both temperature and humidity at all times during both winter and summer seasons. The heating means operated by motor 85 is as much a part of my system as if the same were incorporated in the unit itself since all controls are placed in the recirculated or room air and the admission of steam to the heating means is responsive to the condition of the room air.

Various operations described singularly above may be taking place at the same time, for example, the fresh air dampers may open for just a few seconds and may then close while the steam valves are being opened so that the result of the system is to maintain exact conditions within

the room. A recording instrument placed in an enclosure provided with my system will maintain exactly constant temperature and humidity as long as the capacity of the compressor and the capacity of the radiators is sufficient. It is obvious that during certain periods of the year the cooling effect of outside air will be sufficient to maintain accurately controlled conditions, and also at certain times the heating effect of the compressed gas passing through the reheat coils 31 and 32 will be sufficient so that the steam heating system may be turned off earlier in the spring and later in the fall than is usually the case. Since the demand upon the steam heating system 15 and the refrigerating system is thus restricted to shorter periods of time a direct economy is effected.

Having described my invention it should be apparent to those skilled in the art that various 20 alterations and modifications thereof can be provided, all such as come within the scope of the following claims being a part of my invention.

I claim:

1. An air conditioning system comprising a 25 cooling coil having cooling surfaces so constructed and arranged as to have passage-ways therethrough, said passage-ways being relatively long in one direction whereby air passing through the coil in said one direction remains in contact 30 with said cooling surfaces for a relatively long period of time, and relatively short in the other

direction whereby air passing through the coil in said other direction remains in contact with said cooling surfaces for a relatively short period of time, a duct for the admission of fresh air to said passage-ways and admitting fresh air thereto in the long direction thereof, a second duct for the admission of recirculated air to said passage-ways and admitting recirculated air thereto in the short direction thereof, and interconnected dampers for opening one of said ducts while 10 closing the other, said dampers being so constructed and arranged that the fresh air is confined to traverse the entire length of the coil and the recirculated air is permitted to traverse the width of the coil. 15

2. An air conditioning system comprising a cooling coil having a narrow dimension and a long dimension and passages therethrough in both directions, means to admit fresh air to said system, means to confine such fresh air to traverse said coil in the direction of its long dimension to be cooled and dehumidified thereby, means to admit recirculated air to said system, means to confine such recirculated air to traverse said coil in the direction of its narrow dimension 25 to be cooled and dehumidified thereby to a lesser extent than the fresh air, and means to prevent one type of air from traversing said coil during the time that the other type of air is traversing said coil. 30

CHARLES F. BEELER.
